UNITED STATES PATENT OFFICE.

CHARLES H. BOECK, OF JACKSON, MICHIGAN.

DESIGN FOR A LAMP-STOVE.

SPECIFICATION forming part of Design No. 21,427, dated March 29, 1892.

Application filed February 27, 1892. Serial No. 423,089. Term of patent 14 years.

To all whom it may concern:

Be it known that I, CHARLES H. BOECK, a citizen of the United States, residing at Jackson, in the county of Jackson and State of Michigan, have invented and produced a new and original Design for Lamp - Stoves, of which the following is a specification, reference being had to the accompanying drawing, showing a part thereof.

My design relates to oil or gas stoves; and it consists of a rectangular base with a globe surmounting the same of approximately spherical shape.

In the accompanying drawing, the design is represented in perspective.

The stove-base is of rectangular shape, and upon the base the shade is located, of spherical form.

I claim—

The design for an oil or gas stove, herein shown and described.

In testimony whereof I affix my signature in presence of two witnesses.

CHARLES H. BOECK.
